CLAIM

The ornamental design for an ear spoon, as shown and described.

DESCRIPTION

FIG. 1 is a front elevational view of a first embodiment of an ear spoon showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a perspective view thereof;
FIG. 8 is another perspective view thereof;
FIG. 9 is an exploded perspective view thereof;
FIG. 10 is a front elevational view of a second embodiment of the ear spoon;
FIG. 11 is a rear elevational view thereof;
FIG. 12 is a left side elevational view thereof;
FIG. 13 is a right side elevational view thereof;
FIG. 14 is a top plan view thereof;
FIG. 15 is a bottom plan view thereof;
FIG. 16 is a perspective view thereof;
FIG. 17 is another perspective view thereof; and,
FIG. 18 is an exploded perspective view thereof.
The broken lines in the drawings depict portions of the ear spoon that form no part of the claimed design.
